United States Patent Office

Des. 197,948
Patented Apr. 14, 1964

197,948

FOOT BATH

Joan Barker, 741 N. Beatty St., Pittsburgh, Pa.

Filed July 23, 1963, Ser. No. 75,937

Term of patent 14 years

(Cl. D4—4)

Fig. 1

Fig. 3

Fig. 2

FIG. 1 is a perspective view of a foot bath showing my new design;

FIG. 2 is a top plan view thereof; and

FIG. 3 is a front elevational view thereof.

The bottom, not shown, is substantially plain.

I claim:

The ornamental design for a foot bath, as shown and described.
